UNITED STATES PATENT OFFICE.

GEORGE HIMROD, OF CHICAGO, ILLINOIS.

IMPROVEMENT IN HEARTHS OF COOKING-STOVES.

Specification forming part of Letters Patent No. 43,771, dated August 9, 1864.

To all whom it may concern:

Be it known that I, GEORGE HIMROD, of Chicago, in the county of Cook and State of Illinois, have invented a new and useful Improvement in Hearths or Ash-Boxes for Stoves; and I do hereby declare that the following is a full, clear, and exact description thereof, reference being had to the accompanying drawings, and to the letters and figures marked thereon, which form part of this specification.

In the said drawings, which are hereunto attached, Figure 1 represents a perspective view of my invention.

The nature of my invention consists in a novel arrangement for supporting and retaining in place the removable cover or top of the ash-box in a stove-hearth.

To enable those skilled in the art to understand how to make and use my invention, I will proceed to describe the same with particularity.

A in the drawings represents the ash-box. B is the removable cover or top, raised up to disclose the construction of the parts beneath; and C, the top or surface of the hearth around the removable top B. The hearth is so arranged with respect to the stove that the part marked D is under the stove, and that part of the ash-pit which is contiguous to D and not covered or closed by the removable top B lies directly beneath the grate of the stove to receive the ashes falling therefrom.

a represents a series of vertical ribs or projections cast upon the sides of the ash-pit at suitable distances apart, as shown. These are designed to support the top B, and are all of the same height, and have a flat top, so that said removable top B is adjusted upon them properly. It rests firmly and equally upon the said supports, the top of said cover B lying exactly in the plane of the hearth C.

b b are two small projections cast upon B, as shown, so that when the cover B is placed upon the supports a the said projections b

lock behind the supports a, projecting down below the top, and prevent B from sliding forward over the space beneath the grate.

The ordinary mode of supporting the cover or slide over the ash-box is upon horizontal ledges or shelves along the sides of the box. When this method is employed, the ashes are always getting upon the said shelves or ledges, so that the removable top will not lie down squarely upon the supports, and great inconvenience is occasioned in cleaning the ashes from the supports so as to permit the cover to rest firmly thereon. The casting B is also often thicker in some parts than others, owing to various causes; and in order to fit the casting to its supports, it is often necessary to file away the casting, so as to bring it to the proper thickness at those points where the cover rests upon the supports. It is readily seen that in both these respects my invention possesses great advantages. But, very little ashes, if any, could find lodgment upon the ends of the supports a, and if any should they could be very easily removed. And in regard to filing down the casting B, to adjust it properly, with my arrangement it is only necessary that the filing should be done at certain points where the ends of the supports a rest against it, instead of adjusting the casting its entire length, as is necessary in the ordinary manner of constructing the supports.

Having described my invention, I will now specify what I claim and desire to secure by Letters Patent:

1. Supporting the removable top B upon the isolated supports a, arranged and operating substantially as and for the purposes herein specified and shown.

2. In combination with the above, the employment of the stops or projections b, for the purposes specified.

GEO. HIMROD.
